UNITED STATES PATENT OFFICE

KARL SCHWARZ, OF NUERMBERG, GERMANY, ASSIGNOR TO MASCHINENBAU FIRM,
AUGSBURG-NUERMBERG, A.-G., OF NUERMBERG, GERMANY.

CYLINDER

1,106,977.

Specification of Letters Patent. Patented Aug. 11, 1914.

Application filed March 12, 1912. Serial No. 745,071.

To all whom it may concern:

Be it known that I, KARL SCHWARZ, a subject of the German Emperor, residing at Nuremberg, in the county of Mittelfranken and State of Bavaria, Germany, have invented certain new and useful Improvements in Cylinders, of which the following is a specification.

This invention has reference to improvements in cylinders for double-acting two-cycle internal combustion engines and pertains more particularly to that class of cylinders which is used in Diesel-motors. As is well known to those skilled in the art of constructing such engines, the generation of heat is much greater in double-acting two-cycle motors than in any other motors. It is evident that the generation of heat increases in these motors as well as in all other internal combustion engines in accordance with the number of explosions which take place within a certain unit of time. For this reason the construction of these large double-acting two-cycle cylinders of the Diesel mechanism requires particular skill. Experience has taught that all of these cylinders are especially liable to cracking at or near the stays of the escape slits.

It is the special purpose of the present invention to overcome the described defects. This has been primarily attained by the peculiar construction and arrangement of the various parts hereinafter described and as illustrated on the accompanying drawing which represents in longitudinal central section a cylinder for two-cycle internal combustion engines, embodying in desirable form the present invention.

In the drawing *a*, *a* represents the interior wall of a cylinder constructed in accordance to the present invention, *b*, *b* is the external wall, *c* illustrates the escape slit and *d* an annular bulge around the cylinder covering the escape slit in the manner hereinafter specified. The main feature of this construction is that the escape slit *c* extends around the entire periphery of the cylinder without the provision of any stays. The escape slit is covered by the bulge *d* of such

55
ment for the adjoining portions of said slit which is shown to be of wave-like or serpentine form. The transmission of tension takes place through the outer cylinder wall consequently the two parts of the inner wall may move toward each other in case of unequal heating which can not be avoided in practice. Owing to the yielding property of the bulge the two rims or edges of the slit 60 may also move toward each other in proportion to the expansion of the inner wall caused by the heat.

In the form of cylinder illustrated in the drawing, the escape slit *c* represents an uninterrupted zig-zag line, the bulge being of 65 a shape which is favorable to yielding. I prefer an escape slit forming a zig-zag line because I obtain by this arrangement simultaneously a guide for the piston rings. In this case the rims or the edges of the escape 70 slit may also move freely toward each other.

I claim as my invention:

1. A cylinder for double-acting two-cycle internal combustion engines comprising an interior wall having an annular escape slit 75 interrupting said wall through its entire periphery, an uninterrupted exterior wall, connecting flanges at the end of said walls, and an annular bulge connecting the interior wall portions where they are separated from each other by the escape slit, said bulge forming thus a yielding element.

2. A cylinder for double-acting two-cycle internal combustion engines comprising an interior wall having an annular escape slit 80 of serpentine shape interrupting said wall through its entire periphery, an uninterrupted exterior wall, connecting flanges at the end of said walls, and an annular bulge connecting the interior wall portions where they are separated from each other by the escape slit, said bulge forming thus a yielding element.

In testimony whereof I affix my signature in presence of two witnesses.

KARL SCHWARZ.
